(57) **CLAIM**

The ornamental design for an electrical fitting for non-metallic electrical cables and cords, as shown and described.

DESCRIPTION

FIG. 1 is a top isometric view of an electrical fitting for non-metallic electrical cables and cords showing my new design;

FIG. 2 is a bottom isometric view thereof;

FIG. 3 is a top plan view thereof;

FIG. 4 is a bottom plan view thereof;

FIG. 5 is an end view thereof, with the opposing end view being a mirror image thereof; and,

FIG. 6 is a side view thereof, with the opposing side view being a mirror image thereof.

The broken lines shown in the drawings represent unclaimed subject matter and form no part of the claimed design.
